UNITED STATES PATENT OFFICE.

RENE DE M. TAVEAU, OF ELIZABETH, NEW JERSEY, ASSIGNOR, BY MESNE ASSIGNMENTS, TO THE TEXAS COMPANY, OF NEW YORK, N. Y., A CORPORATION OF DELAWARE.

TREATING HYDROCARBONS.

Application filed March 16, 1923. Serial No. 625,525.

This invention relates to improvements in that method of treating hydrocarbons in which the hydrocarbons are treated with metallic halid catalysts, such as aluminum chlorid, and has special reference to means for effectually carrying on such a process on a commercial scale.

In heating hydrocarbons with aluminum chlorid there are formed certain compounds or admixtures of aluminum chlorid and hydrocarbons and possibly other elements. When carrying on a distillation with the hydrocarbons and the catalyst some of these compounds or mixtures are noticeable in the vapor portions of the still as a red colored liquid which refluxes back to the still if proper conditions in the vapor passages are maintained. Others appear in the form of black, sludgy or tarry materials which tend to settle to the bottom of the still. The apparatus, in which the distillation with the catalyst is carried on, usually includes agitating or scraping mechanism for keeping the chlorid material admixed with the oil and for preventing the adherence of the tarry matters to the heated metallic walls of the still. In practice, however, the carbonaceous or tarry products of the reaction, including the sludgy aluminum chlorid compounds or mixtures, become very thick and viscous as the distillation proceeds and it has been found almost impossible to prevent the baking and coking of these products, with the result that the catalytic properties of the catalyst are lessened or destroyed prematurely and the length of the runs reduced. The attempt to carry on the reaction to completion results in rapid deterioration of the heated metallic walls of the still.

My invention contemplates a method of operation in which the catalytic materials, such as aluminum chlorid, and derivatives thereof formed in the reaction, are prevented from gaining access to those portions of the still to which the heat is applied. I have found that by keeping the catalytic material in the body of the oil in the still and spaced from the heated walls thereof that an effective conversion of higher boiling hydrocarbons into lower boiling ones can be carried on and the reaction carried to completion without danger of the production of any dangerous coke deposits.

Moreover, the invention obviates the use

of scraping or agitating mechanism which has hitherto been considered necessary in the distillation with these catalytic materials and in thus avoiding the use of such mechanism contributes materially to the effective carrying on of the process on a commercial scale.

The accompanying drawing is a diagrammatic elevation partially in section which shows a preferred form of an apparatus constructed in accordance with the invention and constituting an embodiment thereof.

The apparatus thus illustrated includes a still 10 which may be of any suitable form and construction. The still is adapted to be heated by any convenient means, such as the burners 11 arranged in a furnace 12, and may be suitably lagged or insulated in any desired manner.

The still is equipped with a false bottom or receptacle 13 which is adapted to contain the catalytic material and is spaced from those portions of the still to which the heat is applied. As illustrated, the pan or receptacle is shown as having a plurality of legs 14 by which it is supported somewhat above the still bottom to which the heat is applied by the heating means 11. But it is to be understood that the receptacle may be supported in the still in any suitable manner.

Superposed above the false bottom 13 is a deflector 16 which is so arranged as to prevent the flow of material from the upper portions of the still to the bottom thereof and is adapted to direct into the receptacle 13 material collected in the vapor or upper portions of the still. In the specific example of the invention illustrated the deflector is shown as being in the form of a funnel having a peripheral flange 15 by which it is supported on a ledge formed in the wall of the still and to which it may be welded or otherwise secured, if desired. It is to be understood that the member 16 may be supported in the still in any suitable manner; for example, it may be mounted on supports attached to the pan 13. Whatever may be the method of support employed, it is desirable that the deflector be in such contact with the sides of the still as to prevent the passage of any material quantity of condensate down the sides of the still to the bottom thereof and that it be so arranged as

to lead the reflux into the pan 13. The deflector is shown as terminating a short distance above the top of the pan 13 but it may be arranged to depend into the pan if so desired. The funnel-shaped type of deflector I consider the preferable type in the cheese box form of still illustrated. It will be understood by those skilled in the art, however, that various modifications as to form and shape and arrangement may be made within the spirit and scope of my invention. For example, in a cylindrical horizontal still the deflecting means preferably assumes the form of a pair of longitudinally extending plates depending from the upper portion of the still and inclined at such angles as to direct the reflux into the false bottom beneath.

The still is provided with a pipe or conduit 17 for admitting the aluminum chlorid material or other catalyst and with a charging line 18 for introducing the hydrocarbon material to be treated. A draw-off line 19 for the still 10 and an outlet pipe 20 for the pan 13 are also preferably provided. The still is equipped with a vapor line 21 which preferably extends to one or more air condensers 22 or other suitable fractionating or refluxing means. A reflux line 23 is adapted to conduct condensate from the fractionating or condensing apparatus 22 back to the still 10. Preferably the pipe 23 extends to the pan 13, and terminates within a circular baffle 24 so that the flow of liquid into the pan will not so agitate the catalytic material as to discharge portions of same over the rim of the pan. A vapor line 25 extends to a condenser 26 provided with an outlet 27 for discharging the condensed product desired. The outlet may have a pressure regulating valve 28, as the rate of the reaction is accelerated by carrying on the distillation under pressure.

In the operation of the process the hydrocarbon material which may, for example, comprise such petroleum products as gas oil, kerosene, or other hydrocarbon oil, which it is desired to treat for the production of lower boiling hydrocarbons, is introduced into the still through the charging line 18. The catalyst is admitted through the conduit 17. It will be observed that the deflecting means 16 insures that the catalytic material will be disposed in the pan 13. The catalyst may comprise any suitable metallic halid but is preferably aluminum chlorid. The chlorid may be introduced in the form of a liquid, having been previously admixed with hydrocarbon material or other suitable liquid carrier, or it may be introduced without admixture with a liquid solvent or carrier and in the form of granular or lump chlorid. Heat is applied to the still 10 and in the preferred method of operation, as the distillation proceeds, reflux condensation is

carried on in the fractionating or condensing means 22 and those products which are of higher boiling point than that desired are returned to the still or to the pan 13 by the pipe 23. The vapors leaving the still through the vapor line 21 usually contain more or less aluminum chlorid material which is generally observed in the form of a red colored liquid. The temperature in the condensing apparatus 22 is such that no material quantity of aluminum chlorid or aluminum chlorid-containing compounds or mixtures are allowed to enter the vapor line 25, these chlorid materials being returned by the pipe 23 to the still or to the body of catalytic material contained therein. The vapors may also contain a certain amount of aluminum chlorid material which is condensed in the upper portions of the still and in refluxing is guided by the deflector 15 into the pan 13.

It is apparent that in this method of operation no material quantity of aluminum chlorid compound or mixture, constituting potential tar-forming material, and in fact no material amount of the carbonaceous products of the reaction, will be admitted to the bottom of the still 10, these materials being retained for the most part in the false bottom 13. Since the heat is not applied to these bodies directly but on the other hand is transmitted to the catalytic material through the liquid in the still, the baking or carbonizing of the sludge or tarry products is avoided. Moreover, decomposition of the catalytic material is avoided and it is kept in such a condition of fluidity that the reaction proceeds to completion with a maximum production of the low boiling point products desired. The use of agitating or scraping mechanism in the still is unnecessary and in fact does not appear to contribute to the effectiveness of the process, although the practice of the invention does not preclude the use of such mechanism.

In carrying on the process the oil level in the still may be held at any point desired, for example, either above or below the deflecting member 16. In one method of operation a comparatively small quantity of oil is maintained in the still at a level below the top of the pan 13 and oil vapors and vapors containing the catalytic material are driven off with the result that the oil vapors passing up from the annular space about the pan 13 and entering the deflector 16 come in contact with the vapors containing the catalyst which are liberated from the pan 13 and also in contact with the film of reflux containing aluminum chlorid material which is being conveyed by the deflector 16 to the pan 13. In the preferred method of operation the liquid level is held above the top of the pan 13.

The gasoline, naphtha or other product de-

sired enters the vapor line 25 in the form of a vapor, is condensed in the condenser 26 and is removed through the line 28.

If desired the treatment with the catalytic material may be conducted without the concurrent removal of distillate from the treating vessel. Thus the oil to be treated may be introduced into a closed receptacle preferably equipped with a diphlegmator or 5 fluxing means and the oil in contact with the catalytic material subjected to the heat required to effect the desired conversion into low boiling point products. The oil may then be removed and subsequently distilled 10 to recover the light products desired.

The residual material remaining in the receptacle 13 at the end of a run is of an asphaltic character. Its fluidity when in a heated condition enables it to be readily 15 withdrawn from the still. If desired, from time to time during the distillation residue 20 may be withdrawn from either or both of the outlets 19 and 20 and fresh chlorid and oil introduced through the charging inlets 25 17 and 18.

Obviously, various modifications of the invention may be effected without departing from the spirit and scope of the invention.

The true scope of the invention is defined in the appended claims.

30

What I claim is:

1. The process of converting higher boiling hydrocarbons into lower boiling ones that comprises maintaining a body of oil in a still and applying heat to the bottom of the still to heat the oil to a vaporizing temperature while retaining a quiescent pool of aluminum chlorid material within said still, said pool being spaced and separated from the heated bottom of the still.

2. The process of converting higher boiling hydrocarbons into lower boiling ones that comprises maintaining a body of oil in a still, applying heat to the bottom of the still to heat the oil to a vaporizing temperature while retaining a quiescent pool of aluminum chlorid material within said still, said pool being spaced and separated from the heated bottom of the still, periodically charging fresh oil into the still and adding aluminum chlorid to said pool and separately drawing off liquid from said pool and from the bottom of the still.

In witness whereof I have hereunto set my hand this 7 day of March, 1923.

RENÉ DE M. TAVEAU.
